CENTRIFUGAL SEPARATION

Philippe P. Strich, Montreal, Quebec, Canada, assignor to The Western States Machine Company, Hamilton, Ohio, a corporation of Utah

Application December 22, 1951, Serial No. 262,993

6 Claims. (Cl. 210—73)

This invention relates to continuous centrifugal separation.

Trump U. S. Patent 1,933,644, and Sanchez y Cil U. S. Patent 2,096,594, disclose centrifugal separators, using rapidly rotating conical motors, capable of being used to carry out continuous centrifugal separation processes.

These patents discuss the advantages of such processes and describe their application to drying crystals of sugar, salt and other substances. More particularly, the second patent discusses their application to separating molasses or syrup from massecuite.

The first patent provided means for regulating the discharge rate of the centrifuge. But, the means employed is relatively complex, making the apparatus complicated and cumbersome to manufacture, transport, and use.

An object of this invention is to provide a method and apparatus providing for continuous centrifugal separation, by which the discharge of the centrifuge can be controlled within fine limits and can be easily adjusted during the rotation of the rotor.

This and other objects and advantages are accomplished by causing the continuous forward movement of the material being centrifuged through a drying zone solely by centrifugal action, and controlling the introduction of the material to the drying zone by a regulatable control of the discharge of the centrifuge, this discharge being regulated by confining the passage of the material at the end of the drying zone positively by the action of discharge valves which are positioned by a yieldable control force and by a counteracting component of the centrifugal force of said material so that the extent of the discharge opening is easily adjustable during the rotation of the rotor.

This can be done conveniently in accordance with the invention by means of an apparatus having the following features. This apparatus includes a rotor having a peripheral rim. This rim is formed with a plurality of spaced apart outlet ports, and each of these ports is controlled by its own valve means. Common actuating means located on the rotor is provided for actuating all the valve means. And control means independent of the rotation of rotor and located off the rotor, is provided for controlling the actuating means.

More specifically, the apparatus preferably has the following features. The rotor includes a conical perforated basket rotatable on a horizontal axis and having an annular skirt at its periphery. A retaining cone is coaxially arranged within the basket for rotation therewith, the cone also having an annular skirt at its periphery overlapping the basket-skirt to form a composite rim. The skirts are fixedly connected together throughout a major area. The basket and cone form therebetween a main passage for material being centrifuged. Outlet passages between the skirt of the basket and the skirt of the cone are spaced apart about the periphery and extend from the main passage to and substantially radially through the rim. And valve means as referred

2

to above are provided for controlling the flow of the centrifugate or charge solids through each of the outlet passages.

Preferably, each valve means is housed in a recess 5 formed adjacent its outlet passage. Desirably a valve means includes a flap which is articulated to oscillate within the passage, the flap either opening or closing the outlet passage and being urged towards open position by a lateral component of the centrifugal force of material 10 in the outlet passage. The flap is disposed angularly and swingable in the passage in such manner that the lateral force component is greatest when the flap is in its closed position and diminishes as the flap moves away from that position. In this arrangement, the actuating means 15 is preferably an inflatable elastic tube which extends through an annular passage formed between the skirt of the basket and the skirt of the cone. This tube is connected to a conduit located on the rotor and extends therefrom to a rotatable joint at the axis of the rotor. 20 This rotatable joint is connected to a stationary conduit leading to a source of compressed air supply so that the pressure in the ring or tube can be adjusted so as to urge the flap valves towards the closed position with any desired force, or to allow them to be urged by the lateral component of the centrifugal force of the centrifuge towards the open position to increase the opening of the outlet. By changing the air pressure in the tube while the loaded machine is rotated at full speed, the valves can be caused to assume any desired position 25 corresponding to a desired rate of discharge through the outlet passages, since the adjusted air pressure will be counterbalanced by the lateral pressure of the centrifugate against the valve flaps only at a definite different position of these flaps. In this way the extent of opening of each 30 of the outlets can be easily adjusted while the apparatus is in operation and its adjustment is substantially uniform for the various outlet passages throughout the periphery of the rotor.

The invention will be understood in more detail by 40 reference to the accompanying drawings in which a preferred embodiment is illustrated by way of example, and in which:

Figure 1 is a side elevation, partly in section, of a preferred apparatus.

Figure 2 is an enlarged fragmentary cross-section taken 45 close to the outlet periphery of the basket.

Figure 3 is a vertical cross section along the line 3—3 of Figure 1.

Figure 4 is a front elevation partly in section showing 50 particularly the arrangement of the valves controlling the outlet ports.

Figure 5 is an enlarged fragmentary vertical cross section along the line 5—5 of Figure 4, showing the valving arrangement.

Figure 6 is an enlarged fragmentary vertical cross section along the line 6—6 of Figure 4.

Referring more particularly to the drawings, the apparatus includes a foundation A carrying an electric motor B and pedestals 14 for main bearings C of the 60 centrifugal apparatus. The main bearings C carry a horizontal hollow shaft 15. On one end of the shaft 15 is mounted a pulley 17 about which passes a plurality of endless belts 19 driven from a pulley 22 which in turn is mounted on the shaft 23 of the electric motor B.

On the other end of the shaft 15 is mounted the centrifugal rotor D including two centrifugal cones, one an outer basket 25 and the other an inner cone 30. The cones 25 and 30 are separated by a space 28 in which the massecuite will travel. The wall of the basket 25 70 may be similar to the walls of an ordinary vertical basket used in separating sugar, but the holes allowing the syrup to be spun off preferably are on the same circle

and are preferably situated as close as possible to the places of division or partition between the zones of separation of the first and second syrups, between the zones of separation of the second syrup and sugar, and so on. One or two large mesh screens can be used, but the screen in contact with the massecuite must have perforations as small as consistent with good operation. Screens 26, 26a and 26b of increasing mesh size here line the inner face of the basket 25. These screens space apart the sugar from the inner wall of the basket 25 and give the syrup a chance to separate from it. This will be understood by those skilled in the art.

The basket 25 has an outwardly-extending annular skirt 50 on which there is an inwardly extending annular flange 49. The flange 49 serves to bear against the ends of the screens 26, 26a and 26b preventing them from slipping forward. The cone 30 also has an outwardly-extending annular skirt 43 which overlaps the skirt 50 of the basket and is removably connected thereto by bolts 58a. To the skirt 50 is fixed, also by the bolts 58a, a ring 51. This ring 51 has a structure shown in the drawings and to be described. The structure formed by the skirt 50 and the ring 51 includes recesses constituting outlets and an annular housing for valve means controlling them.

To explain, the ring 51 includes a continuous recess 52 in its forward face, which extends about its entire periphery. Likewise, the skirt 50 includes a continuous recess 58b in its rear face forming with the recess 52 throughout the major portion of the annular housing a passage E for an inflatable elastic tube 75. The outer faces of the ring 51, skirt 50 and skirt 43 constitute a cylindrical end face of the rim of the rotor.

Spaced apart about the skirt 50 are openings 55, each joining the space 28 and extending to an outlet 55a in the end face of the rim of the rotor. Each opening 55 is bordered at the rear thereof, beyond the tube passage E, by a recessed forward face portion 55b of the skirt 50, which is spaced from the adjacent rear face portion of the skirt 43. Forward face portions 55c of skirt 50 separate the openings 55, being arranged to meet and seal against the rear face of the cone-skirt 43. In communication with the tube passage E, each opening 55 has a relatively deeply recessed portion, as seen at F in Fig. 5, which extends through skirt 50 and into an indentation 51a in ring 51. Each recess F is bordered at its inner end by a wall 55d in skirt 50. Each recess F provides a housing for a valve arrangement. It is important to note that side walls 55e and 55f of each opening 55, as seen in Fig. 4, converge toward the outlet 55a, so that the openings 55 taper from wide mouths at their inner ends adjacent to the main passage 28 to relatively narrow outlets at their outer ends. So the centrifugate, that is the solid component of the charge material, such as sugar, is concentrating in approximately triangular outlet passages toward a relatively small outlet at the apex of each passage. The flap of the valve controlling these outlets in the preferred arrangement is also triangular in shape.

Thus between them the skirt 50, the ring 51 and the skirt 43 enclose the channel E extending about the periphery of the rotor D and the spaced apart passages 55 which serve as outlets from the centrifuging space 28 and merge with deeper recesses or pockets F which constitute housings for a valve arrangement controlling these outlets.

The inner cone 30 is provided at its smaller end, as seen in Fig. 1, with a diagonally-inwardly-extending annular flange 40 forming a feeding cone.

The actuating means for controlling the outlet openings 55 includes the following features. For each opening there is a flap valve having a flap 57 which is articulated to the skirt 50 by brackets 57a bolted to the skirt. The flap 57 is located at a point close to the wall 55d,

and it has side edges near the walls 55e and 55f and a tip overlapping the recessed face 55b of the skirt 50.

Each flap 57 is connected by a screw 65 to a flanged tubular socket 66 having an annular flange 67. A screw 68 is set as at 69 into the ring 51. Each screw 68 carries a spring 70 which acts on the flange 67 between it and the head of the screw tending to draw the tip of the flap 57 towards the surface of wall 55b on which it seats.

The tubular ring 75 of elastic material, preferably of rubber or synthetic rubber, extends about the annular channel E and bears against the rear face of the flap 57 which preferably includes a boss 57c adapted to engage the tube 75.

A conduit 78 held on the basket 25, leads from the ring 75 to a conduit 79 passing through an opening 80 in the ring 51 as shown in Fig. 2, and is adapted to supply air to the tube 75. This conduit continues through part 82 and concentrically within the hollow shaft 15 and connects with the special revolving joint 83. A valve 84 connected to the stationary pipe 85 which is connected to the other side of the joint 83 controls the supply of air to the tube 75.

A pipe 90, concentric to the cone, extends from the forward end thereof for introducing charge material to be centrifuged, for example, massecuite. The pipe 90 ends adjacent to the feeding cone 40 of the inner basket 30.

A water pipe 92 extends from a suitable source of water supply to adjacent the inner end of the inner cone 30. The inner cone 30 is provided with an inwardly-extending baffle 31 and openings 32 to oblige the water to enter the space 28 between the two cones.

The entire rotor assembly up to its rim is surrounded by a stationary receptacle 33 which has an annular end wall 34 near the smaller end of the basket 25, another end wall 35 near the rim, and an intermediate partition 36 which divides the receptacle into separate compartments for collecting liquids expelled from the charge material in different zones of the basket. A discharge pipe 96a extends from the bottom of the first compartment of receptacle 33 to allow one purged liquid, say the green syrup in sugar processing, to be drawn off; while the farther compartment is provided with a discharge pipe 96b for taking off another liquid such as the wash syrup produced in sugar processing.

A discharge hood 97 envelops the front of the cone to catch the centrifuged solids, for example, sugar, projected from the openings 55, and a pipe 98 leads from the hood 97 to carry off these solids.

The two cones 25 and 30 are not homothetic, that is, the inner surfaces of the cones tend to converge towards the front or wider side of the cone. Also, the outer cone or basket is reinforced as at 25a because centrifugal force tends to break the basket.

Operation

An illustrative cycle of operation of the apparatus as used for centrifuging sugar massecuite is as follows:

The machine is started and the cones are rotated at a speed of between 1500 and 2000 R. P. M., preferably around 1800 R. P. M., depending upon the diameter of the rotor and the centrifugal effect desired in its operation.

The massecuite is fed directly from the usual mingler preferably after passing the massecuite through a small press after the mingler. Usually the massecuite is heated to about 130° F. The massecuite passes from the press and arrives at the discharge end of the pipe 90 and enters the feeding cone 40. Centrifugal force causes the massecuite to proceed outward on the cone 40 and whence it enters the space 28 between the cone 30 and the basket 25. The space 28 becomes filled with massecuite and remains filled with massecuite in its various degrees of extraction, the product, of course, being centrifuged sugar at the outlet end. The converging of the surface

of the basket 25 and cone 30 is designed to keep a substantially constant speed of the sugar along the screen. Immediately the massecuite is projected onto the walls of the basket 25 the green syrup is extracted progressively as it travels outwardly on the surface of the basket 25. The syrup goes out through the holes 25b. When the extracted sugar approaches the outer end of the centrifuge it passes through the discharge outlets controlled by the valves 57.

The inner surface of the basket 25 is, practically speaking, divided into a purging zone which extends substantially between the inner opening and the second opening 25b, a washing zone which extends substantially between the second opening and the third opening and a drying zone which extends substantially between the third opening and the final opening. The rough location of these zones is shown between the chain lines. The centrifuge is well dried crystalline sugar.

Air pressure in the elastic pipe 75 is adjusted until good sugar is coming through the outlets. A skilled operator can tell by the appearance of the sugar when it is of proper quality. For any given speed of basket rotation and type of charge material, the solids in the outlet passages will have a certain centrifugal force which will be exerted against the valve flaps 57 when the flaps are fully closed and will produce a different lateral component of force against these flaps for each different angular position of the flaps. Since this lateral component of force urges the flaps away from their closed position in opposition to the air pressure in tube 75, and since it diminishes as the extent of opening of the outlet passages increases, the extent of such opening is determined by the magnitude of the air pressure in tube 75 and can be adjusted to give any desired rate of discharge simply by adjusting the air pressure without changing the operating speed of the machine.

Water is introduced continuously through the pipe 92. So, in effect, the zone between the water inlet 32 and the third circular series of basket openings is the washing zone.

While the preferred form of the actuating means has been shown as pneumatic, it is understood that this could, in the broader aspects of the invention, take other forms. For example, it could be operated mechanically or electrically. But, the pneumatic form is the preferred one.

The parts will, of course, be made of suitable materials as is well understood by one skilled in the art. The tube 75 must, of course, be suitable durable resilient material like rubber, or one of the synthetic rubbers.

While the invention has been described particularly in connection with the separation of sugar from massecuite, it will be understood that it is also applicable to other centrifuging problems of an equivalent nature, particularly where a solid has to be separated from a liquid. It also will be understood that the particular embodiment here shown and described is merely illustrative and that many alterations and substitutions can be made in it while still making use of the subject matter herein disclosed and claimed as my invention.

I claim:

1. A centrifugal machine comprising a conical perforated basket adapted to be rotated continuously at a high speed, said basket having an annular skirt at its outer margin, a retaining cone within the basket for rotation coaxially therewith, said cone having an annular skirt at its outer margin overlapping the skirt of said basket and being fixedly connected thereagainst throughout a major area thereof, said basket and cone forming therebetween a main passage for material being centrifuged, a circular series of separate outlet passages between the skirt of the basket and the skirt of the cone, each of said passages having a relatively wide mouth connected with said main passage and converging to a relatively narrow outlet at the outer periphery of said skirts, said basket skirt having a recess therein at one side of each of said outlet passages,

each of said recesses including a shallow apex portion opening at the periphery of said skirt and a deeper recessed portion terminating in an end wall near the inner end of the outlet passage, a valve flap articulated to the basket skirt in each deeper recess portion adjacent to its said end wall, said flap being seated on said apex portion in an open position and forming a side wall portion of the outlet passage that is swingable between said open position and a closed position in which it extends towards said cone skirt at an increased angle to the path of discharge of material in the outlet passage, the lateral component of the centrifugal force exerted on said flap by such material being substantially greater when the flap is in said closed position than when it is in said open position, a tube channel interconnecting said deeper portions of said recesses about the circumference of said basket, an expandable tube in said channel to urge all of said flaps towards said closed position, and a fluid supply tube connected with said expandable tube and extending from it away from the basket for conducting fluid under pressure into said tube to regulate the position of said valve flaps.

2. A centrifugal machine as described in claim 1, and spring means normally urging each of said valve flaps towards said open position.

3. A centrifugal machine as described in claim 1, the skirt of said cone forming the forward side wall of each of said outlet passages.

4. A centrifugal machine comprising a conical perforated basket adapted to be rotated continuously at a high speed, said basket having an annular skirt at its outer margin, a retaining cone within the basket for rotation coaxially therewith, said cone having an annular skirt at its outer margin overlapping the skirt of said basket and being fixedly connected thereagainst throughout a major area thereof, said basket and cone forming therebetween a main passage for material being centrifuged, a circular series of separate outlet passages between the skirt of the basket and the skirt of the cone, each of said

passages having a relatively wide mouth connected with said main passage and converging to a relatively narrow outlet at the outer periphery of said skirts, said basket skirt having a recess therein at one side of each of said recesses including radially spaced inner and outer forwardly facing surfaces spaced from the cone skirt, a deeper recessed portion between said surfaces, and oppositely facing lateral walls meeting the cone skirt to define lateral sides of the outlet passage, a valve flap articulated in the deeper portion of each recess near said inner surface thereof, said flap having sides flush with said lateral sides thereof and a tip adapted to seat on said outer surface thereof in one position and to seat on the cone skirt in another position, a lateral component of centrifugal force urging the valve flap in each outlet passage towards said one position during the operation of the machine, actuating means for urging such valve flap towards the cone skirt in opposition to said component of force, and control means extending away from the basket and cone and operable independently of their movement for adjusting the force of said actuating means so as to control the position of such flap valves during such operation.

5. In a continuously rotated centrifugal machine comprising a rotary tapered basket and a coaxial rotary retainer spaced inwardly from the basket, the basket and retainer defining therebetween an annular passageway of progressively increasing diameter for material being centrifuged and forming a discharge rim at the larger end of said passageway, a substantially radial outlet passage in said rim communicating with said annular passageway for discharging centrifuged material, a valve element forming a wall portion of said outlet passage and movable laterally therein to and away from a position in which it substantially closes the path of discharge of material therein, said valve element having a face disposed obliquely across said path when in said position so that a lateral component

of the centrifugal force of material in said passage urges said element laterally away from said position while the machine is operated, the magnitude of said force component diminishing as said element is moved laterally away from said position, and yieldable means for urging said element toward said position with a counterbalancing force sufficient to maintain a desired degree of opening of said outlet passage.

6. In a continuously rotated centrifugal machine comprising a rotary basket having a perforated conical side wall and a coaxial rotary retainer secured to the basket and spaced inwardly from said side wall, the basket and retainer defining therebetween an elongated annular passageway of progressively increasing diameter for material being centrifuged and forming a discharge rim at the larger end of said passageway, a plurality of circularly spaced outlet passages extending substantially radially from said annular passageway through said rim for discharging centrifuged material, a separate valve element in each of said passages forming a lateral wall portion thereof and movable laterally therein to and away from a position in which it substantially closes the passage, said valve element in each passage being disposed obliquely across the same when in said position so that a lateral component of the centrifugal force of material in the passage urges the valve element laterally away from said

position while the machine is operated, the magnitude of said force component diminishing as said element is moved laterally away from said position, fluid pressure responsive means operative upon the valve elements of all of said outlet passages for yieldably urging the same toward said position, and means connected with said fluid pressure responsive means and extending away from said basket for regulating the force of said fluid pressure responsive means so as to position said valve elements at any desired degree of opening of said outlet passages.
